UNITED STATES PATENT OFFICE.

HERON J. KRESKY, OF MARYSVILLE, CALIFORNIA, ASSIGNOR TO EDWARD C. NEWTON, OF MARYSVILLE, CALIFORNIA.

MAGNETO-GOVERNOR.

1,339,655.

Specification of Letters Patent. Patented May 11, 1920.

Application filed January 19, 1917. Serial No. 143,322.

To all whom it may concern:

Be it known that I, HERON J. KRESKY, a citizen of the United States, residing at Marysville, county of Yuba, and State of California, have invented certain new and useful Improvements in Magneto-Governors, of which the following is a specification.

This invention relates to a magneto driving connection adapted to be mounted on the armature shaft of the magneto and connected with the crank shaft of the engine so that it is rotated thereby.

The principal features of the invention consist in combining in a unitary structure a universal coupling, an automatic spark advancing device and an impulse starter; in the arrangement of the parts whereby the spark advance is not operative until after the impulse starter is inoperative; the impulse starter not only intermittently accelerates the armature but such acceleration takes place through the strongest portion of the magnetic field and as the distributor or breaker box is not retarded gives absolutely the most efficient spark possible under the conditions of slow running; and while the impulse starter is operative the spark cannot occur before the dead center position of the engine.

Other features will be apparent from the description taken in connection with the drawings in which,

Figure 1 is a perspective view of the device with the parts in disassembled position;

Fig. 2 is a view similar to Fig. 1 but viewing the parts from the opposite end of the device;

Fig. 3 is a longitudinal sectional view of the assembled device;

Fig. 4 is an end view showing the stop which cooperates with the impulse starter.

The device comprises a cylindrical shell 10 formed at one end with an inwardly extending flange 11 which is provided with a series of uniformly spaced apertures 12. A disk or flange 13 is adapted to be arranged in substantially the same plane with the flange 11 and the outside diameter of said flange 13 is smaller than the inside diameter of flange 11 whereby flange 13 may be arranged inside of flange 11. Near its periph-

ery this flange 13 is formed with a series of uniformly spaced apertures 14 similar to 55 the apertures 12, and a coil spring 15 is adapted to have its coils interlaced through the said apertures 12 and 14 thereby connecting the two flanges 11 and 13. The flange 13 is formed with an axially extending hub 16 which is exteriorly threaded and may be slotted as at 17 so that the nut 18 when screwed upon the same will clamp the said hub 16 onto a driving shaft 19 which may be rotated from the crank shaft 65 of the engine. Other suitable means might be used to connect the flange 13 so that it is rotated by the engine crank shaft. It will thus be apparent that the flanges 11 and 13 with the interlaced spring 15 form 70 a universal coupling which permits a slight disalignment of the axis of the hub 16 with respect to the axis of the casing 10.

At the end of the casing 10 opposite the universal coupling an impulse starter is arranged and between these two parts and in the interior of the casing an automatic spark advancing mechanism is housed. The casing 10 at the end having the flange 11 but arranged slightly inward from the same has 80 a radially extending flange 20 which is formed with a centrally located bore 21. At its opposite end the said casing is formed with a counter-bore 22 in which is fitted the plate 23 which is formed with a centrally arranged stub shaft 24 extending toward the universal coupling. This stub shaft or stud is formed with the reduced portion 25 which is adapted to be seated in the bore 21 and with the threaded portion 26 which is 90 adapted to take the nut 27 so that the inner periphery of the flange 20 is loosely arranged between the said nut and the shoulder portion 28 of the stub shaft 24. Thus the plate 23 is securely held against longitudinal movement with respect to the casing 10 but may rotate slightly relatively to the same. The face of the plate 23 opposite that having the stud 24 is formed with two annular channels 29 and 30 and with the 100 centrally arranged circular opening 31 which leads into the recess 32 formed in the central portion of the plate. The outer or rim portion of the plate 23 carries two segmental cams 33 which extend into the channel 28 and have their inner surfaces 34 flat,

The channel 29 has a coil spring 34 seated therein with one end abutting against a projection 35 carried by the plate and the other end free and spaced slightly from the said projection. The segmental cams 32 are arranged diametrically opposite and the space between the end of spring 34 and the projection 35 is in line with these two cams. As clearly shown in Fig. 1 the casing 10 is provided on its interior surface with a plurality of annular toothed segments 36 which are uniformly spaced around said surface. The stud 24 on the plate 23 is formed with a corresponding number of toothed segments 37 which are arranged opposite the annular toothed segments 36. Centrifugal dogs or levers are arranged in the space between the stud 24 and the casing 10 and provided with teeth 38 which are adapted to mesh with the teeth on the annular segments 36 and with oppositely arranged teeth 39 which are adapted to coöperate with the teeth 37 on the stud. The teeth 38 and 39 in effect constitute a mutilated gear, that is, a gear having some of its teeth cut away. Extending laterally from the teeth 38 and 39 is an arm 40 which under the action of centrifugal force tends to turn the lever or dog so as to move the stud 24 angularly with respect to the casing 10. While three of these centrifugal dogs or levers with the weighted arms 40 are shown it is apparent that any other desired number might be used. A spring 41 is arranged between the flange 20 of the casing and the stud 24 and has one end connected with said flange and the other end with the stud. Between the spring and the adjacent faces of the centrifugal levers a disk 42 may be arranged so as to prevent interference of the spring and the levers. The parts just described constitute the spark advancing mechanism and its operation will be explained hereinafter.

As previously stated, the impulse starter is arranged at the end of the casing opposite the universal coupling and consists of parts which are adapted to coöperate with the cams 32 and the coil spring 34 carried by the plate 23. The cover 43 is arranged at the end of the casing 10 with its outer surface flush with the outer surface of the casing 10, and is provided with a centrally arranged bore 44 adapted to receive the armature shaft 45 of the magneto. Any desired means may be used to connect the cover 43 and the shaft for rotation together. In its interior the cover 43 is formed with an axially projecting pin 46 which is adapted to seat in the space between the free end of the coil spring 34 and the projection 35. It is also formed with an axially extending hub portion or sleeve 47 arranged around the armature shaft, and with two diametrically opposite apertures 48 extending through its shell. Two oppositely arranged latches are mounted in the interior of the cover and each has an end 49 which is adapted to project a slight distance through one of the apertures 48 and outside of the cover so that it may be caught by the stop 50 carried by the stationary bracket 51. These latches are formed with an enlarged central opening 52 which is adapted to take over the hub 47 and permit a sliding movement of the latch transversely of the axis of the device. The end 49 is normally held in projected position by means of a spring 53 which is seated in a recess 54 in the latch and operative between the bottom of said recess and the hub 47. Opposite the end 49 each latch is provided with a weighted portion 55 which is formed with a slot 56 in which the stem portion 57 of the other latch is adapted to slide. Each latch has the stem portion provided with an axially extending pin 58 which is adapted to coöperate with the cams 32. As the stem portion of one of the latches is arranged behind the weighted portion 55 of the other, this latter weighted portion is formed with a slot 59 through which the pin 58 on the stem portion of the other latch projects. The impulse starter is assembled with the pin 46 in its position between the free end of spring 34 and the projection 35 and with the pins 58 on the latches at substantially 45 degrees with respect to the cams 32.

The magneto connection is adapted to be connected with the armature shaft of the magneto so that the impulse starter when the latch is free from the stop 50 will accelerate the armature through the strongest portion of the magnetic field of the magneto, thus giving the most efficient spark. It will be noted that there is no manually operated breaker box or distributor to be retarded when starting the engine and consequently the spark may occur at the most efficient point in the rotation of the armature. It is also intended that the magneto connection shall be mounted on the armature shaft so that the spark, when the impulse starter is operative, cannot occur before the engine has reached dead center position.

In the operation of the device the rotation of the shaft 19 through the universal coupling will cause the rotation of the casing 10. It will be noted that the coupling will take care of any disalignment between the shaft 19 and the armature shaft thus permitting the armature shaft to be driven without any binding even if the two shafts are not in line. The rotation of the casing 10 by means of the intermeshing teeth on the centrifugal levers will rotate the plate 23. The direction of rotation of the device is indicated by the arrows in Figs. 1, 2 and 3 and it will be noted that this direction is such that it tends to turn the centrifugal levers so that the cams 40 are caused to contact with the

stud 24. Furthermore, the spring 41 is tensioned so that it tends to hold said arms against the stud 24. Hence in order to cause the armature shaft to advance relative to the casing 10 it is necessary for the speed of the driving shaft 19 to be such that it will develop sufficient centrifugal force in the arms 40 to overcome the torque being transmitted through the levers and also the tension of spring 41. These forces which are utilized to resist the outward movement of arms 40 are designed so that said arms will not move outward to advance the spark of the engine until after the impulse starter has become inoperative. The rotation of casing 10 is thus transmitted to the stud 24 which in turn through the projection 35 and circularly arranged coil spring 34 acts on the pin 46 of the cover to turn the latter. As this cover 20 turns one of the ends 49 on the latch will be caught by the stop 50 thus holding the cover against rotation. While the cover is thus held the plate 23 will continue to rotate thus compressing the spring 34. When the said plate has rotated substantially 45 degrees relative to the cover 43 the pins 58 will come into operative position with respect to the cams 32 and the said cams will push the pins inward thereby moving the end 49 of the latch free from the stop 50. The spring 34 will thus be liberated and its energy will accelerate the plate 43 so that the armature of the magneto will be turned very rapidly through the strongest part of the magnetic field thus producing a very efficient spark. As the engine picks up speed the centrifugal force developed by the weights 55 on the ends of the latches will move the latches transversely across the axis 30 of rotation thus withdrawing the ends 49 within the cover 43 and out of position where they might be caught by the stop 50. It is obvious that the starter may be designed to become inoperative at any desired speed. As previously stated the relation between the impulse starter and the automatic spark advancing device is such that the spark advancing device does not become operative until the impulse starter has become inoperative. Thus when the engine has reached a speed sufficient to render the impulse starter inoperative the centrifugal force developed in the arms 40 of the spark advancing device will be sufficient to overcome the forces 50 resisting outward movement of said arms and they will move out an amount in proportion to the rotative speed of the device. This outward movement will cause the stud 24 to be angularly advanced with respect to the casing 10 thus through the connected parts advancing the armature shaft so that the spark in the engine will occur earlier. It will thus be apparent that a universal coupling spark advancing mechanism and impulse starter are combined in a unitary

structure which may be attached to any standard magneto. Furthermore the impulse starter and spark advancing mechanism operate independently of each other, that is the acceleration of the armature shaft 70 due to the impulse starter does not in any way affect the spark advancing mechanism. This is due to the fact that the impulse starter is arranged between the magneto and the spark advancing mechanism. 75

Having thus described the invention what is claimed and desired to be secured by Letters Patent is:

1. A unitary magneto driving connection comprising in combination a universal coupling adapted to be attached to a driving means, a continuously acting automatic spark advancing mechanism responsive to the speed of the driving means and a device for intermittently retarding and accelerating the angular velocity of the armature shaft. 80

2. A unitary magneto driving connection comprising in combination a universal coupling at one end of the connection adapted 90 to be attached to a driving means, a device for intermittently retarding and accelerating the angular velocity of the armature shaft at the other end, and a speed responsive continuously acting spark advancing 95 mechanism interposed between the coupling and device.

3. In a magneto driving connection adapted to be interposed between a driving member and the magneto armature shaft, an impulse starter adapted to become inoperative above a predetermined angular velocity and spark advancing mechanism responsive to the speed of said driving member. 100

4. In a magneto driving connection adapted to be interposed between a driving member and the magneto armature shaft, spark advancing mechanism responsive to the speed of said driving member, and an impulse starter adapted to become inoperative above a predetermined angular velocity interposed between said mechanism 110 and the armature shaft of the magneto.

5. In a magneto driving connection adapted to be interposed between a driving member and the magneto armature shaft, an impulse starter adapted to become inoperative above a predetermined angular velocity and a speed responsive spark advancing mechanism which is operative only above said velocity. 115

6. In a magneto connection an impulse starter comprising a plate member having a pair of diametrically oppositely disposed cams and a circularly arranged coil spring, an abutment on said plate for one end of said spring, a member adapted for attachment to the armature shaft and having a pin engaging the other end of the spring, and carrying two telescoped radially mov- 125 130

able latches arranged to coöperate with a fixed stop and each having a pin adapted to coöperate with a cam and be moved inwardly thereby to trip the latch from the stop.

7. A magneto driving connection comprising a casing having a universal joint at

one end for connection to a driving member, an impulse starter rotatively mounted at the other end and a speed responsive spark advancing means between the joint and starter. 10
In testimony whereof I affix my signature.

THERON J. KRESKY.
